UNITED STATES PATENT OFFICE

GEORGE E. O'HEARN, OF GARDNER, MASSACHUSETTS

DESIGN FOR A CHAIR OR SIMILAR ARTICLE

Application filed September 16, 1931. Serial No. 41,119. Term of patent 7 years.

To all whom it may concern:

Be it known that I, GEORGE E. O'HEARN, a citizen of the United States, residing at Gardner, in the county of Worcester and State of Massachusetts, have invented a new, original, and ornamental Design for a Chair or Similar Article, of which the following is a specification, reference being had to the accompanying drawing, forming part thereof.

The figure is a perspective view of a chair showing my new design.

I claim:

The ornamental design for a chair or similar article as shown.

GEORGE E. O'HEARN.
